WINDOW

David A. Seligman, New York, N. Y.

Application April 2, 1934, Serial No. 718,603

4 Claims. (Cl. 20—49)

My present invention relates more especially to windows for use in various types of buildings.

An object of the invention is to provide a window structure admitting of a variety of oblique positions of the sash for ventilating and cleaning, the structure in all oblique settings being secure, and in the conventional setting thereof being at least as secure and more rattleproof than windows of conventional construction, the sashes of which have only sliding adjustment.

Another object is to provide a construction of the above type involving simple, inexpensive parts, rugged in construction and easily assembled, installed and manipulated by the occupant or tenant for various settings thereof, all without the need for mechanical skill, or the use of tools, or the likelihood of loosening parts or scraping the paint from the window sash or frame.

Another object is to provide a window sash construction of the above type which may be readily and conveniently substituted at relatively small expense for the conventional window sashes of existing buildings, without the need for expert carpenter's service.

According to a feature of the invention a conventional sash is used, slidable in the window frame as a unit with lateral sheet metal track members guided by the grooving of the window frame. The sash has a pivot or trunnion mount in the lower ends of said tracks, and one or more links connecting one or both sides of the sash to the associated track to limit the forward pivoting of the sash about its trunnion mount.

According to another feature, the link is pivoted at both ends but has a slide block mount at one end, preferably at the track end, to permit the forward and return pivoting movement of the sash. The link may be of such length and so correlated with the elements it connects as to permit setting the sash at proper angle for ventilation or, if desired, may be of such length and so correlated as to permit setting the sash at proper angle for convenient cleaning of the outside of the pane from within the building.

According to another more specific feature, two links are provided at one, but preferably at each of the sides of the sash, each link slideable at one end along the track and pivoted at the other end to the side of the sash. The shorter of the links, determining the extreme ventilating position of the sash, is readily re-

leasable at one end thereof to permit further forward pivoting of the sash for convenience in cleaning the outside of the pane from within the building.

According to another feature, both the longer link and the shorter link have a common pivot mount at the sash, from which pivot the shorter link is readily removable by a convenient resilient pivoting fit.

Another feature is the use of a sheet metal angle plate presenting a ledge protruding from the sides of the sash for cooperation with the track, an associated latch serving to lock the sash to the track when in closed position.

In the accompanying drawings in which are shown one or more of various possible embodiments of the several features of the invention,

Fig. 1 is an elevation of the window in closed position.

Fig. 2 is a view in longitudinal cross section through the sash with parts broken away.

Fig. 3 is a view in longitudinal cross section along line 3—3 of Fig. 2, showing the sash in ventilating position.

Figs. 4, 5, 6 and 7 are transverse sectional views taken respectively on lines 4—4, 5—5, 6—6 and 7—7 of Fig. 2.

Fig. 8 is a view in longitudinal cross section, taken on line 8—8 of Fig. 4.

Fig. 9 is a view in transverse cross-section, taken on line 9—9 of Fig. 8, and

Figs. 10, 11, 12, 13 and 14 are transverse sectional views on a smaller scale, showing various alternative settings of the two sashes in a window frame.

Referring now to the drawings, there is shown in Fig. 1 a conventional window-frame F having therein the usual two sashes S, which, however, as will appear more fully hereinafter, are of widths somewhat smaller than conventional for the frame, the intervening elements presently to be described, compensating for the difference in width.

Referring more particularly to Figs. 2 and 4 to 7, inclusive, each window sash S has trunnion pins 20 protruding laterally therefrom near the lower end thereof and bearing in metal blocks 21 slideable with the sash in the conventional runways 22 of the window-frame. The blocks are rigid with sheet metal track members 23 lining the runway of the window frame and movable along said runway in the sliding movement of the sash.

The forward pivoting movement of the sash about its trunnion pins 20 is limited by means

now to be described. For this purpose, as best shown in Figs. 3 and 6, a sheet metal link 25 is pivoted by means of rivet 26, at one end thereof to a sheet metal slide block 27 near the lower 5 end of the track and slidable longitudinally therealong. The track has ridges 28 thereon to confine enlargements 29 on said slide block. The upper end of link 25 is pivoted to the sash by means of a screw 30 protruding laterally from 10 the sash. By this arrangement it is clear that as the window sash is pivoted forward about its trunnion mount 20, the slide block 27 at the lower end of the link 25 will slide upward. The track 23 is formed with a lug 31 either cut out 15 or soldered or brazed to the track serving as a stop for the slide block, to limit the forward pivoting movement of the sash, in the present instance, to a position best shown in Fig. 14 convenient for washing the outside of the pane 20 from within the building.

In addition to the link 25 set forth, a second and shorter link 35 is provided at one side, but preferably at both sides of the window-sash, said link pivoted at its lower or inner end, as 25 best shown in Figs. 3 and 5 by means of rivet 36 to a slide block 36 near the upper end of the track 23, all in manner identical to the slide block connection of link 25.

The outer or upper end of the shorter link 35 30 also has a pivot connection to the side of the sash. The latter pivot connection, which is preferably on the same stud 30 which affixes the upper end of link 25, is preferably of the construction best shown in Figs. 3, 8 and 9. According to this construction, the link 35 has a pair of parallel slits 37 determining a tongue 38 therebetween, the upper end of which is widened at 39 and notched at 40, to determine the lower half of a circular aperture, the upper 40 part of which appears at 41 and is rigid with the body of the link. The head of the stud 30 is grooved at 42 so that the aperture in the link 35, by virtue of the resilience of tongue 38 will readily snap over the head 42 of the stud to form 45 a secure friction hold thereover, which, however, permits the slight rotary displacement incurred in pivoting movement of the sash.

It is, of course, understood that the longer link 25 may be at one side of the sash and the 50 shorter link 35 at the opposite side of the sash, or that both links, as shown, may be at one and the same side of the sash, but preferably two pairs of the links are used, one pair at each side of the sash.

55 It is clear that as the window sash embodying both the longer link 25 and the shorter link 35 is pivoted outward from normal position, the two slide blocks 27 and 36 slide upward along the track 23 until slide block 36 strikes the 60 abutment 43 in the track by which the latter is connected to the counterweight cord 44. In that position, best shown in Figs. 3 and 11, the sash is in a preferred ventilating position.

When it is desired to wash the outside of the 65 window-pane, the shorter link 35 is simply pushed outward away from the sash to release it from friction stud 30, whereupon the sash can be pivoted forward considerably farther to the limiting position, shown in Fig. 12, in which 70 the slide block 27 is arrested by stop 31.

To restore the sash to position, it is obvious 75 that the forward end of the shorter link 35 is first snapped back in position about its pivot 30 and the sash is pushed back into the window frame about its trunnion pins 20, in which ac-

tion the two slide blocks 36 and 27 will move downward along their tracks and the links will become confined in superposed position between the sides of the sash and the tracks, as best shown in Figs. 4 and 5.

In order to effect a secure fit of the sash with respect to the tracks 23, a metallic interlock between said elements is preferably provided. In the specific embodiment shown, the sheet metal track 23 is preferably provided with a 10 unitary reversely bent longitudinal ledge 45 at the advanced end thereof, said ledge protruding laterally inward from the side of the window-frame and constituting a sheath. The sash is provided with a sheet metal angle 15 plate 46, having a longitudinal ledge 47 spaced from the edge of the sash itself and fitting snugly in the sheath 45 on the track 23, as best shown in Figs. 4, 5 and 6. By this arrangement, a secure rattle-proof substantially air-tight connection between the sash and the window-frame is effected. In order to avoid excessive strain on the sheath 45 in pushing the sash back to home position, it is preferred to provide a rearward extension ledge 48 on the track which 20 will take the rearward thrust of the sash, as best shown in Figs. 4, 5 and 6.

While the frictional hold set forth between the sash and the tracks may be sufficient, it is preferable to provide a positive latch between 30 said elements. One embodiment of such latch is best shown in Fig. 8. As shown, said latch comprises a loop 50 struck out from the sheath 45 of the track 23 and a hook 51 integral with the upper end of the angle bar ledge 47. The angle bar 46 may be longitudinally displaceable along the window sash to set the latch, for which purpose said angle bar is connected to the window sash by screws 52 through vertical elongated slots 53. The upper end of the angle 40 bar is provided, as best shown, in Figs. 8 and 9 with a thumb piece 54 which, when pushed downward sets the latch, and thus locks the sash in the track and window frame, and when pushed upward releases the latch to permit 45 pivoting displacement of the sash. The specific thumb piece arrangement, just set forth, is most convenient for the lower sash. For the upper sash it is preferred instead of the thumb piece to use hinged finger pieces 55, as best 50 shown in Fig. 1, and also to connect the upper ends of the angle pieces 46 by a sheet metal cross bar 56 affixed also by screws 57 in vertical elongated slots 58.

It will of course be apparent, that the latch 55 shown is merely illustrative, and that any of a wide variety of latching or fastening instrumentalities may be employed for releasably connecting the sash to the track to afford a rigid sliding assembly when the sash is to be positioned in the manner of conventional sashes.

The mode of use of the sash will be readily understood from the drawings, in connection with the foregoing description, but Figs. 10 to 14 give a pictorial indication of the flexibility 65 of use of the installation.

The setting of Fig. 10 permits of burglar-proof locking of the lower sash without preventing ventilation through the upper sash shown in ventilating position. Fig. 11 shows 70 both sashes in ventilating position, and is effective for liberally admitting air, but excluding rain and to a large degree excluding noise. Fig. 12 shows the lower sash in position for washing, although of course, that position may be 75

adopted also for ventilation, as shown in Fig. 14, with respect to both the window sashes. Fig. 13 shows the lower sash set in position for ventilating purposes with the elimination of the auxiliary ventilator commonly used in substantially that position for such purpose.

While the drawings show the conventional wooden sash, it will, of course, be understood that the invention is also applicable to metal sash windows.

It will also be understood that while a long and a short link are preferably used in the specific manner and for the purpose set forth, it is within the scope of the broader claims to use but a single link or a single pair of links to admit but of one limiting position, for the sash reasonably suitable both for ventilation and for washing the exterior pane.

While the invention is of course suitable for new building constructions, it is applicable to existing buildings as well, without involving the slightest alteration or rebuilding of the conventional window-frame construction thereof. All that is necessary is to replace the window sashes by other sashes of otherwise conventional construction, but slightly narrower, with their associated tracks and links, the weight cord being attached to the tracks in the manner previously set forth.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent is:

1. A window structure including a sash of the type having a sliding and a hinging movement, said sash having lateral metal tracks adapted to slide therewith in an associated window frame and having a pivoted connection at the lower end thereof between the lower ends of said tracks, metal slide blocks at the lower ends of

said tracks, links pivoted at their lower ends to said slide blocks and pivoted at their upper ends to the sides of said sash, said tracks having stops to limit the upward movement of said slide blocks for defining the outermost pivoted position of the sash. 5

2: A window structure comprising a sash having lateral tracks slidable in an associated window frame, said sash pivoted between the lower ends of said slideable tracks, and having means at its sides for secure releasable friction mount between said tracks, each of said tracks having a slide block therein, links pivoted to said slide blocks at one end thereof and having at the other end thereof a quick detachable friction pivot connection to the sash, said friction mount comprising a circular stud protruding from the sash, said link having a struck-out elongated tongue, one end of which defines a part of a circular aperture about said stud. 10 15

3. A window comprising a frame, a sash having trunnions at the lower end thereof slid- able in said frame, said sash in closed position having a lateral friction mount with respect to said frame, a pair of links connecting said sash 25 with respect to said frame, said links including a longer link having a slide block at one end thereof, movable along said frame, and a shorter link having a slide block at one end thereof, movable along the frame, both of said links 30 having a pivoted connection laterally of the sash, the pivot connection of the shorter of said links with respect to the sash being of the quick- detachable friction type. 35

4. A window sash, a frame therefor, a trun- nion mount near the lower end of said sash, slid- able in said frame, links limiting the pivot- ing movement of said sash about said trunnion, said links comprising a pair of longer links, each having a slide block movable along the frame 40 and near the lower end thereof, each of said links having a pivot mount with respect to the corresponding side of the sash, a pair of shorter links at opposite sides of the frame, each of said shorter links having a slide block at one end 45 thereof substantially above that of the corresponding longer link, the forward end of each of said shorter links having a friction pivot con- nection to the sash, at the pivot connection of the longer link, the sash pivot connections of 50 the shorter links being of the quick-detachable type.

DAVID A. SELIGMAN.
